UNITED STATES PATENT OFFICE.

GEORGE H. EARNEST, OF SPRINGFIELD, OHIO, ASSIGNOR OF ONE-HALF TO
NELLIE D. FUNK, OF SAME PLACE.

COMBINED MATCH-SAFE AND CIGAR-CUTTER.

SPECIFICATION forming part of Letters Patent No. 623,206, dated April 18, 1899.

Application filed March 29, 1898. Serial No. 675,567. (No model.)

To all whom it may concern:

Be it known that I, GEORGE H. EARNEST, a citizen of the United States, residing at Springfield, in the county of Clark and State of Ohio, 5 have invented certain new and useful Improvements in a Combined Match-Safe and Cigar-Cutter, of which the following is a specification.

My invention relates to improvements in 10 combined match-boxes and cigar-cutters; and the object of my invention is to provide a combined match-box and cigar-cutter for use on show-cases or counters, the different parts of which are so formed that neither screws 15 nor bolts will be required in its assembling.

The invention consists in the various constructions and combinations of parts herein-after described, and set forth in the claims.

In the accompanying drawings, Figure 1 is 20 a side view of my device, some of the parts being broken away. Fig. 2 is a front view of my device, some of the parts being broken away. Fig. 3 is a sectional view taken on the line $x-x$ in Fig. 2. Fig. 4 is a perspective 25 view of some of the parts in detail. Figs. 5, 6, and 7 are detail views in perspective of parts of my device.

Like parts are represented by similar letters of reference in the several views.

30 In constructing my device I employ a base or standard a , which is provided with the upwardly-extending flange a' and the inner laterally-extending flange a'' . The flange a'' on opposite sides of said base is provided with the slots a^3 , having offset portions a^4 . Secured to said base are the side pieces a^5 and a^6 , each of which is cut away at its lower end to form a T-shaped lug a^7 . The arms of said lug are adapted to stand below the part of the 35 flange a'' adjacent to the offset portion of the slot a^3 . The side pieces are held in position by a locking-plate a^8 , formed with depending flanges a^9 , which are adapted to fit in the offset a^4 of the slots a^3 in the base. The side 40 pieces are provided with flanges a^{10} , which are formed at their long edges. Said side pieces are grooved adjacent to said flanges, which, together with the flanges, form ways for holding the front and rear plates in position. I provide a top plate for all, having

depending flanges which are adapted to fit around the four side pieces. On the lower part of the casing thus formed and adapted to slide on the locking-plate a^8 is the drawer 55 a^{12} . Above the drawer is the supporting-plate b , which is made in two sections, as shown in Fig. 5. This plate is formed with ears b' , which are adapted to stand within slots b^2 in the side pieces a^5 and a^6 . Above and resting on the plate b is the sliding plate 60 b^3 . This plate is provided on its under side with the flanges b^4 and b^5 , which rest on the plate b . At one side of the plate b^3 is the projecting pin b^6 , which extends through a slotted opening b^7 in one of the side pieces a^6 . 65 Resting on suitable lugs b^8 and b^{15} on the side pieces, above the moving plate b^3 , is a plate b^9 , which is provided on one side with a match-trough b^{10} , having a cut-away portion b^{11} , in which is adapted to move a projecting finger 70 or ejector b^{12} , formed on the moving plate b^3 . The part of the plate b^9 above and adjacent to said trough is formed in the nature of a sliding bearing-surface c . Adapted to slide laterally on said bearing-surface is the feeding-plate c' . Said plate extends upwardly at 75 an angle from said bearing-surface to one of the side pieces, against which it rests. This feeding-plate has a lug c^3 , which extends down through a slot c^2 in the plate b^9 and into a 80 diagonally-extending slot c^4 in the moving plate b^3 . This feeding-plate is formed with an offset portion c^0 or with the lower part in a different plane than the upper part, as shown in Figs. 2 and 6.

85 On the side piece a^5 , above the plate b^9 , is a series of inwardly-extending ribs c^5 , which are triangular in cross-section. Said rib extends into the casing, and its inner end is adapted to stand adjacent to the jointure of 90 the two portions of the feeding-plate.

The side piece a^5 is provided with a hole c^6 , and adjacent to said hole is pivoted a knife c^7 , having an upwardly-extending arm c^8 , adapted to oscillate within a groove c^9 in one 95 side of the moving plate b^3 .

Fitted in a suitable channel c^{10} in the moving plate is a spring c^{11} , one end of which abuts against a projection on the flange b^5 , while the other end bears against a lug on the 100

front plate of the casing. This spring is adapted to hold the sliding plate b^3 in its normal inward position.

On the outside of the side piece a^6 I pivot 5 a bell-crank lever d . One end of the lever projects out in front of the casing and the other end extends upwardly through a slot b^{14} on the plate b and is bifurcated and adapted to engage the pin b^6 on the sliding plate b^3 .

10 The operation of my device is as follows: By removing the top the matches may be placed in the chamber above the feeding-plate c' , as shown in Fig. 2. The lever d is then depressed, and by so doing the sliding plate 15 will be carried forward and with it the knife, which will close the hole c^6 . As the sliding plate moves forward the feeding-plate will be raised or moved and the space between it and the flange c^5 adjacent thereto will be enlarged and some of the matches will move 20 down into the trough b^{10} . When the lever is released, the parts will be carried to their normal position by means of the spring. As the lever is again depressed the finger b^{12} on 25 the sliding plate will contact with the lowest match in the trough and force the same out of the casing through an opening b^{13} in front of the trough for that purpose.

The drawer acts as a receiver for the tips 30 of the cigars which are cut off by the knife.

It will be noticed that in the above construction the parts are all formed to fit together and be held in position without the use of any bolts or screws, thus making the 35 construction very simple and inexpensive.

It should be noted that the feeding-plate c' at the corner between the main plate and the offset portion c^0 forms, with the triangular rib c^5 , a throat, which when the plate is in 40 the normal position is closed, preventing the entrance of a match at this point; but when the plate is moved to allow the match to be engaged by the ejector then this throat is opened just sufficiently to admit one match 45 and one only, so that all danger of clogging is thus prevented, a sufficient clearance being left below this throat and at the offset portion c^0 to permit the matches to descend freely from this point to the trough, so as to 50 be engaged by the ejector, thus insuring the proper delivery of the matches and also preventing more than one match from being discharged at any one point.

In order that the matches may enter the 55 throat in proper position to be engaged by the ejector, it is necessary that they be prevented from slipping endwise on the feeding-plate c' into the space between the end of the feed-plate and the rear of the casing, and to 60 accomplish this the said space is preferably closed above the ejector in any suitable manner, a plate D , placed adjacent to the end of the feeding-plate and extending from the plate b^9 to the top of the casing, being shown 65 for this purpose, said plate being held in position by small lugs on the sides of the casing.

Having thus described my invention, I claim—

1. In a combination match-box and cigar-cutter, an outer casing formed of side pieces 70 having engaging flanges, front and rear pieces held in position by said flanges, a base with slots adapted to engage projections on the side pieces, a locking-plate for locking said side pieces to said base, a movable member with- 75 in said casing, a feeding-plate and a match-ejector operated by said movable member and supported by said locking-plate, substantially as specified.

2. In a combination match-box and cigar-cutter, side pieces having engaging flanges and front and rear pieces adapted to be held in position by said flanges, a base having slots adapted to engage projections on the side pieces, and a locking-plate for locking said 85 side pieces to said base, substantially as specified.

3. In a combination match-box and cigar-cutter having slotted side pieces as described, a two-part supporting-plate having projec- 90 tions to engage the slots of said side piece, a sliding plate supported by the supporting-plate, a trough-plate above said moving plate, and a feeding-plate above said trough-plate, and means outside of said casing for moving 95 said sliding and said feeding plates simultaneously, substantially as specified.

4. The combination with a base having a laterally-projecting slotted flange, of side pieces having projections adapted to stand 100 within the slots of said flanges, and a locking-plate having depending lugs or flanges also adapted to stand within said slots, said plate forming means for locking said side pieces to said base, substantially as specified. 105

5. The combination with side pieces having slots and flanges as described, of a two-part supporting-plate having ears thereon, the respective parts of said plate being adapted to stand between the side pieces while the ears 110 thereof stand in said slots, said ears being formed with projections adapted to conform to the flanges on said side pieces, the ears adjacent to one of said side pieces meeting to form a slot between themselves and said side 115 pieces, substantially as specified.

6. The combination with the side pieces and a two-part supporting-plate standing at right angles to said side pieces and having ears adapted to be fitted into slots in the side pieces 120 from opposite sides thereof, said ears being formed so that they will meet on the outside of said side piece, of a lever having a projection adapted to fit in an opening in the side piece to move a sliding and a feeding plate, 125 one arm of said lever standing within the space between the ears and the side piece, and held in position by said ears, substantially as specified.

7. The combination with a sliding plate 130 having a projecting finger thereon, and a diagonal or cam opening in said plate, a plate

suspended above said moving plate and provided with a match-trough at one side thereof in line with the projecting finger on the sliding plate, a feeding-plate extending upwardly from said trough at an angle to the sliding plate, a projection on said feeding-plate standing in said cam-opening, and a lever for operating the sliding plate thereby moving said feeding-plate to and from said trough, substantially as specified.

8. The combination with a sliding plate having a diagonal slot or cam-opening, of a feeding-plate adjacent to said sliding plate

and formed with a projecting lug adapted to stand within said cam-opening, a lever connected to said sliding plate to move said sliding and feeding plates from their normal positions, and a spring adjacent to the sliding plate adapted to return said plates to their normal positions when said lever is released.

In testimony whereof I have hereunto set my hand this 23d day of March, A. D. 1898.

GEORGE H. EARNEST.
